UNITED STATES PATENT OFFICE.

WALTER A. SHEAFFER AND CRAIG R. SHEAFFER, OF FORT MADISON, IOWA.

DESIGN FOR A FOUNTAIN-PEN DESK STAND.

Application filed June 15, 1925. Serial No. 13,794. Term of patent 14 years.

To all whom it may concern:

Be it known that we, WALTER A. SHEAFFER and CRAIG R. SHEAFFER, citizens of the United States, residing at Fort Madison, Iowa, in the county of Lee and State of Iowa, have invented a new, original, and ornamental Design for a Fountain-Pen Desk Stand, of which the following is a specification, reference being had to the accompanying drawing, forming a part thereof.

The figure illustrates a perspective view of a fountain pen desk stand.

We claim:

The ornamental design for a fountain pen desk stand substantially as shown.

In witness whereof, we have hereunto subscribed our names.

WALTER A. SHEAFFER.
CRAIG R. SHEAFFER.
